Attorney

Patented Aug. 26, 1924.

UNITED STATES PATENT OFFICE.

HERMAN H. WENTHE, OF CHICAGO, ILLINOIS, ASSIGNOR TO MEYER & WENTHE, OF CHICAGO, ILLINOIS, A COPARTNERSHIP CONSISTING OF GUSTAVE A. MEYER AND HERMAN H. WENTHE.

SEAL PRESS.

Application filed July 23, 1923. Serial No. 653,126.

To all whom it may concern:

Be it known that I, HERMAN H. WENTHE, citizen of the United States, residing at Chicago, in the county of Cook and State 5 of Illinois, have invented certain new and useful Improvements in a Seal Press; and I do hereby declare the following to be a full, clear, and exact description of the invention, such as will enable others skilled 10 in the art to which it appertains to make and use the same.

My invention relates to seal presses in which one die portion is continuously urged away from the other die portion by a spring, 15 and in which the die portions are approached by the movement of a suitably disposed lever. Generally speaking, my invention aims to provide a novel construction and arrangement of the spring means for urging 20 the cooperating die portions away from each other, aims to provide novel and conveniently disposed means for latching the operating lever in a certain position, and aims to provide a simple and inexpensive mount- 25 ing for the spring and the latching means, together with simple means for holding the latching means in either the latching or unlatching position.

Viewed in some of its more particular aspects, my invention provides a retracting 30 spring adapted to be housed entirely in the upper portion of the press body so as not to require the lower portion of the body to be hollowed out; provides a spring for this 35 purpose which can readily be formed of a resilient wire and which will exert an effective spring action through a considerable range of movement while occupying a relatively small space; and also provides simple 40 means for holding such a spring in its operative position.

Furthermore, my invention provides latching means in which the movable latching member is carried by the lever of the press; 45 provides simple means for guiding the latching member, which guide means can readily be made integral with a handled lever formed of sheet metal; provides a latching member having stop formations engaging 50 the guide means to limit the movement of the latching member in each direction; provides friction means for preventing an accidental movement of the latching member, and desirably employs the said guide means for

holding the friction member in its operative 55 position.

Moreover, my invention provides simple means on the press body for interlocking with the latching member and desirably disposes the last named means so that the same 60 will also serve the purpose of retaining the spring in proper position within the body of the press when other parts of the press are detached from this body. Still further and also more detailed objects will appear 65 from the following specification and from the accompanying drawings in which—

Fig. 1 is a perspective view of a seal press of a pocket type embodying my invention. 70

Fig. 2 is a central and longitudinal section through the same press.

Fig. 3 is a section similar to a portion of Fig. 2, but taken with the lever in its depressed position to show the locking operation of the latching member. 75

Fig. 4 is a fragmentary bottom view of the lever, showing the disposition of the latching member on the same.

Fig. 5 is a transverse section through the handle of the lever, showing the mounting of the latching member. 80

Fig. 6 is a perspective view of the spring employed in the press.

Fig. 7 is a perspective view of the movable die plate with the finger-carrying sleeve bolted to the same. 85

Fig. 8 is a fragmentary plan view of the press with the handled lever and the spring omitted, showing the guiding of the lifting finger by the walls of the chamber in the press body, and also showing the pin which cooperates with the latching member on the handle. 90

In the drawings, I am showing an embodiment similar in some features to that shown in U. S. Patent No. 1,253,756 issued to me January 15, 1918 on an impression seal. In that patent I disclosed a press construction employing a hollow metal body 100 formed of sheet metal and having a die-raising spring disposed within this hollow body and extending through both the upper and lower portions of this body.

In practice, variations in the drawing of the metal make it difficult to form metal bodies of this type with the desired degree of exactness, and the availability of fine

aluminum castings make a cast body desirable as a substitute for pressed steel bodies. However, while the cast aluminum affords the desired lightness, it does not readily lend itself to such an extensive amount of coring as would be required for the spring arrangement shown in my said copending patent, hence my present invention in one of its features provides a body and spring construction permitting the use of a much more compact spring and one in connection with which a much more limiting coring of the press body will be sufficient.

In the illustrated embodiment, the body 1 of the press has a solid lower portion provided at its rear end with a looped handle 2 and provided at its forward end with a disk portion 3 upon which the lead counterpart 4 of the engraved die 5 is formed. This die 5 is threaded upon the lower end of a bolt 6 extending through a sleeve 7, and the said sleeve is slidable in a vertical bore which merges at one side into a chamber 9 formed in the upper part of the press body. The sleeve 7 desirably has its lower end equipped with teeth for engaging the upper end of the stem 10 of the die 5, so as to prevent this die from rotating with respect to the sleeve, and the sleeve also carries a finger 11 extending laterally into the chamber 9 and guided laterally by the walls of that chamber adjacent to the vertical bore in which the sleeve slides, thereby preventing the stem 6 and the die plate 5 from rotating with respect to the press body and the counter die 4 after the manner disclosed in my said U. S. Patent No. 1,253,756.

Interposed between the finger 11 and the bottom 12 of the chamber 9 is a compression spring 13 which has its lower arm portions in engagement with the said bottom and which has an upper arm portion underhanging and continuously engaging the finger 11. For this purpose, I desirably employ a spring formed of a single strand of resilient wire doubled upon itself to form a bight 14 adapted to underhang and engage the finger 11, the doubled wire having an upper arm portion 15 leading from this bight and connected by a coiled portion 16 to lower arms 17, and also having a bend between the upper arm portion 15 and the bight portion 14 as shown in Fig. 6. Each of the lower arms 17 desirably terminates in a downwardly bent tip portion 18 which normally extends through a corresponding perforation in the bottom 12 of the chamber in the press body, so that these perforations together with the underhanging of the finger 11 by the bight 14 of the spring cooperate in retaining the spring in its operative position without requiring auxiliary fastening members. The spring as thus described is desirably formed original-

ly with its upper and lower arms 15 and 17 diverging at a considerable angle after the manner shown in Fig. 6, so that when the spring is in its normal position, it is continually under compression. Owing to this compression, it continuously tends to lift the sleeve 7 and the movable die 5 which is clamped to this sleeve by the bolt 6, the extent of the lifting movement being limited by the engagement of the stem 10 of the movable die with the bottom of the upper portion as shown in Fig. 2.

To move the said sleeve and the die plate 5 downwardly against resistance of the spring, I desirably employ a forked lever pivoted to the press body on a pivot pin 19 and having a handle 20 overhanging the press body, this lever having a pair of rollers 31 continuously engaging the top of the die plate 5 at opposite sides of the bolt 6. The lever as thus arranged desirably has its main portion formed from a single piece of sheet metal and preferably has its handle portion of a downwardly concaved section as shown in Fig. 5.

To latch the lever in its depressed position when the seal press is not in use, I mount a latching member 22 on the handle 20 and provide a latching pin 21 on the press body adapted to be underhung by the said latching member. With this in mind, I desirably punch two pairs of opposed guide ears 23 and 33 from the metal of the handle, with the ears of each pair extending towards each other within the concaved handle formation so as to present upper surfaces spaced from the adjacent bottom portions of the handle, thereby affording a space in which the latching member can slide back and forth. To move it for this purpose, I bend the rear end of the latching member downwardly to afford a finger-piece 24 which can readily be reached by a finger of the hand holding the press, so that the user can manipulate the press with one hand if he so desires. This finger-piece desirably is so positioned that it can engage the rear pair of guide ears 33 to limit the forward sliding movement of the latching member as shown in Fig. 3 and the latching member desirably has a bend formed in the same and adapted to engage the forward guide ears 23 as shown in Fig. 2 to limit its rearward sliding.

To prevent the latching member from accidentally sliding out of the position to which it has been digitally moved, I provide suitable friction means associated with it. For this purpose, I am here showing a U-shaped spring 25 formed of wire and having its bight engaging the lower face of the latching member, this spring being retained in one position by having its bight butt against forward guide fingers 23 and

having its shanks extending under the rear guide fingers 23 at opposite sides of the latching member.

By employing a substantially U-shaped spring, I am able to dispose this in its entirety within a chamber formed only in the upper part of the body of the press, thereby simplifying the casting to a form which can readily be manufactured out of cast metal. Moreover, when the die 5 is detached by unscrewing the bolt 6, the latching pin 21 engages the upper arm portions of the spring so as to serve as a guard for retaining the spring within the chamber 9 without requiring any auxiliary means for this purpose. Since this pin, which extends across the chamber 9 as shown in Fig. 8, is the only additional member required as part of the latching arrangement which is not formed integral with the press body and lever, it will be obvious that the entire construction is exceedingly simple and inexpensive. Furthermore, while the finger-piece 24 is within easy reach of the user of the press, this finger-piece cannot swing into the path of the lever after the manner of latching hooks heretofore employed in such presses, nor will the friction spring 25 permit it to shift out of the position to which it has been moved by the user of the press.

However, while I have illustrated and described my invention as embodied in a portable press having a ring-shaped handle at one end of the body, and one in which the guides for the movable latching member are formed integral with the handle, I do not wish to be limited to these or other details of the construction and arrangement thus disclosed. Obviously, many modifications might be made without departing either from the spirit of my invention or from the appended claims.

I claim as my invention:—

1. In a seal press, a body having spaced horizontal upper and lower arms, a die on the lower arm, the upper arm having a vertical bore and a chamber extending laterally from the bore, a die-carrying plunger slideable in the bore, a finger fixed to the plunger and extending within the chamber, a lever for operating the plunger, and a spring carried in its entirety by the upper arm and disposed within the chamber and engaged with and between the finger and the bottom wall of the chamber.

2. In a seal press, a body having spaced horizontal upper and lower arms, a die on the lower arm, the upper arm having a vertical bore and a chamber extending later-

ally from the bore, a die-carrying plunger 60 slideable in the bore, a finger fixed to the plunger and extending within the chamber, a lever for operating the plunger, and a spring carried in its entirety by the upper arm 65 and composed of a length of wire doubled upon itself intermediate its ends to form upper arms and lower arms each connected by a coiled portion, the upper arms being engaged with said finger and the lower arms having free ends which are turned 70 downwardly and engaged in perforations provided therefor in the bottom wall of the chamber.

3. In a seal press, a body having spaced horizontal upper and lower arms, a die on 75 the lower arm, the upper arm having a vertical bore and a lateral chamber communicating therewith, a die-carrying plunger slideable in the bore, a lever for operating the plunger, and a spring carried in its entirety 80 by the upper arm and engaged with the plunger and with the bottom wall of the chamber.

4. In a seal press, a body having spaced horizontal upper and lower arms, a die on 85 the lower arm, the upper arm having a vertical bore and a lateral chamber communicating therewith, a removable die-carrying plunger, slideable in the bore, a lever for 90 operating the plunger, a spring in the chamber engaged with the plunger to tension same, a pin extending across the plunger in a position to engage the spring and retain same in the chamber upon removal of the plunger, and latching means carried 95 by the lever and movable into the chamber and in engagement with the pin to retain the lever in depressed position against the tension of the spring.

5. In a seal press, a body having spaced 100 horizontal upper and lower arms, a die on the lower arm, the upper arm having a vertical bore and a lateral chamber communicating therewith, a die carrying plunger slideable in the bore, a spring means in the chamber for tensioning the plunger, a lever for operating the plunger, a keeper in the chamber, and a latch carried by the lever and movable into the chamber and in engagement with said keeper to hold the lever 105 depressed against the tension of the spring said plunger being removable and said keeper being disposed so as to engage the spring means and retain same in the chamber upon removal of the plunger. 110

Signed at Chicago, Illinois, July 20th, 1923.

HERMAN H. WENTHE.
